UNITED STATES PATENT OFFICE

2,494,419

TOTALIZATOR

Roy E. Wells, San Mateo, Calif.

Application October 9, 1942, Serial No. 461,473
In Australia June 28, 1938.

2 Claims. (Cl. 235—92)

1

This invention has reference to improvements in totalizators for use upon racecourses, or in conjunction with a race such as a horse race, and which provides for the issue of betting tickets in respect of the various competitors. The present application is a continuation-in-part of application Serial No. 280,183, filed June 20, 1939, and now abandoned.

Various types of totalizators have been devised from time to time, and their construction has been determined by the betting facilities demanded of them. For example, some totalizators provide for speculation only as to the winner of a race; others provide for speculation as to competitors coming, first, second or third in a race; and others provide for speculation on the possibility of two competitors gaining first place, one in one race, and one in another. The foregoing examples are usually designated "Win," "Place," and "Doubles" totalizators, respectively.

The dividend payable in respect of the successful competitor or competitors is determined in each instance, by the ratio of the number of tickets issued in respect of that competitor or competitors, to the number of tickets issued in respect of all of the competitors in the race or races concerned, a deduction having first been made from the total amount of money invested, to provide for taxes and operating expenses.

More particularly, the present invention has been devised with the object of providing a totalizator capable of being operated in respect of the above three examples of speculation. That is to say this invention will provide for tickets being issued concurrently to persons backing a competitor to win, or to come first, second or third in a race, or with a second competitor in another race, to constitute a successful "Doubles."

The present invention can be applied conveniently to existing "Doubles" totalizators of at least one known form wherein the indicating drums are operated electro-magnetically.

In the known form, the "Doubles" totalizator has a plurality of numerical indicators arranged in parallel rows, vertically and horizontally. Each of the horizontal rows indicates the respective competitors in one race, and each of the vertical rows indicates the respective competitors in the other race upon which "Doubles" may be backed, at the choice of the person participating. Other rows of numerical indicators may be included for a "Win" tote and a "Place" tote or the "Win" and "Place" totes may be arranged in separate groups. In conjunction with the to-

2

talizator there are windows or stations from which tickets on the races are sold to investors.

In the above known form of "Doubles" totalizator it is customary to have the tickets assembled for sale in a rack supported adjacent to the selling stations. Each of the tickets when sold, bears two numbers representing respectively the competitors which are selected by the investor as a "Double." As a ticket is issued the numbers on the ticket are communicated by the seller to an operator stationed at a switchboard. The operator depresses the respective switch corresponding to the respective numbers of the competitors selected in both races on which the "Double" is backed, closing an electric circuit to a solenoid provided for operating the numerical indicator at the position vertically and horizontally corresponding to the two competitors comprising the "Double."

Simultaneously with the movement of the particular "Doubles" indicator mechanism referred to above, a separate indicator is caused to display to the public the grand total of tickets sold in respect of the two races for which the "Doubles" tickets are being issued. In the operation of the above known form of "Doubles" totalizator, difficulty is experienced in coping with the demands of prospective investors, as the operator at the switch board often cannot keep pace

with the rate at which the tickets are sold.

An object of the present invention is to provide automatic means for reducing the amount of manual labor found necessary to operate indicating apparatus such as that in the above known form of "Doubles" totalizator, and provide efficient means whereby the issuing of the tickets may be considerably expedited, and whereby the usual numerical indicator drums will be caused to operate automatically and practically simultaneously with the selling of the tickets.

The present invention includes two selector switches incorporated in a ticket issuing machine one of which machines is disposed at each ticket selling station, each selector switch having a switch arm common to a plurality of contacts, one contact being provided for each competitor in a race or races as the case may be. Where a "Win" or "Place" tote are provided for a contact is provided for each in conjunction with one of the selector switches.

The function of the ticket issuing machine and selector switches thereof is to print and issue a ticket in a known manner, but chiefly to provide means for selectively supplying current for an operating mechanism which, subsequently, re-

sults in the sale of the ticket being indicated on the above referred to totalizer drums. In carrying out the invention means are provided whereby the respective ticket issuing machines are locked until ready for the sequence of ticket issuing steps. Each ticket issuing machine has a control handle, the chief function of which is to complete the circuits determined by the setting of the above selector switches and provide a source of current for operating the totalizer drum solenoids.

Provision is also made whereby in the operation of the numerical indicators, current is supplied to means thereon for indicating faults.

The apparatus also includes a distributing device the function of which is to receive current impulses from the respective contacts of the respective ticket issuing machines, and provide a circuit to the solenoids operating the respective indicating drums. This distributing device also provides for the supply of positive current to safety magnets used in conjunction with a switch controlling gear.

Means are also provided to control the current when a plurality of issuing machines is in use in order that more than one of said machines will not register at the same time, thus avoiding a false indication of bets or tickets issued. Such means may include double throw switches operated electromagnetically.

The mechanism for operating the indicating drums may be of a known form, depending for its operation upon a solenoid operated feed mechanism. In the present invention a mechanism is provided between the solenoid and the ratchet whereby, should the drum or its mechanism be inoperative, an electric warning circuit is established.

In order that the invention may be more readily understood, reference will now be made to the accompanying drawings wherein:

Fig. 1 is an elevation of the ticket issuing machine used in conjunction with the present invention, one of which will be used at each ticket issuing station.

Fig. 2 is a diagrammatic elevation of the distributing device, showing one of the oscillating drums mounted eccentrically in the framework.

Fig. 3 is a diagrammatic perspective view of three banks of double throw switches used to control the current when four issuing stations are in use, so that two issuing machines will be unable to register an investment simultaneously.

Fig. 4 is a detail view showing the means adapted to rotate the numeral indicator drums on the face of the totalizer.

Fig. 5 is a view of portion of the face of a known totalizer, showing the vertical and horizontal rows for the various competitors, spaces for the particular race in question and the grand total window in the center.

Figures 6 and 7 illustrate the complementary face plates of the ticket issuing machine with their respective competitor contacts set in the arcuate insulating strips.

Fig. 8 is a longitudinal section through one of the ticket issuing machines, showing part of the ticket printing mechanism with its associated locking pawl and lock plate; the two selector switch arms with their respective contact points; and a portion of the control handle with its associated contact plate at the left.

Fig. 8a is sectional view taken on the line 8a-8a of Fig. 8.

Fig. 9 is a fragmentary section on the line 75

9-9 of Fig. 8 showing the printing anvil; the roller therefor which is operated by the control shaft so as to raise the printing anvil against the printing rollers, and ticket feed rollers at the left.

Fig. 10 is an enlarged section on the line 10-10 of Fig. 2 showing the eccentric mounting of the oscillating drums of the distributing device.

Fig. 11 is a detail view in rear elevation of three of the numeral drums as seen in dotted lines in Fig. 4.

Fig. 12 is a section on the line 12-12 of Fig. 8 indicating the relative position of the main fixed contacts of the issuing machine in their insulated disc.

Fig. 13 is an elevation of the "Vulcanite" disc shown in Figure 12 with its associated metal contacts.

Fig. 14 is an elevation of the moving contact plate which is preferably of spring steel and is complementary to the contact disc of Fig. 12.

Fig. 15 is a diagrammatic view showing a circuit arrangement for the respective parts of the invention.

Fig. 16 is a diagrammatic view of other circuits of the apparatus illustrating the means for preventing simultaneous operation of two machines.

One of the ticket issuing machines, shown in Fig. 1, is illustrated in longitudinal section in Fig. 8 and comprises two complementary face plates 301 and 302 as seen in Figs. 6 and 7. These face plates are bolted together through holes 20 in lugs 22 and the bolts are shown at 20a in Fig. 1.

An indicator strip 21 of approximately semi-circular shape is disposed outwardly of the face plates. As illustrated in Figs. 1 and 8 the strip 21 is secured to the lugs 22. This indicator strip 21 is divided into the required number of divisions according to the number of competitors provided for on the totalizer and one division is marked W and one marked P where a "Win" and a "Place" tote are provided for, each division on the strip corresponding to one of a series of contacts 23 set in an arcuate insulating strip 24, there being two such strips, 24, one on each of the inner surfaces of the respective face plates Fig. 6 and Fig. 7.

Each ticket machine has two selector switch arms 25 and 26 provided with spring contacts 27 and 28, respectively, which are adapted to engage the respective competitor contacts 23. The arms 25 and 26 are securely attached to respective printing wheels 29 and 30, shown in Figs. 8 and 9, which are mounted upon a shaft 31 concentrically disposed with respect to the competitor contacts 23 and the indicator strip 21. The switch arms 25 and 26 are disposed between the respective face plates 301 and 302.

Each selector switch arm 25 and 26 has formed integral therewith a pointer 32 and 33 respectively enabling the operator of the machine to readily select the required competitor on the indicator strip and simultaneously register the switch arm with the corresponding competitor contact 23 as explained later.

In order to obtain correct registration of the printing wheels 29 and 30 and the contacts 23 during the issuing of a ticket to an investor, a spring detent 34 is provided on each of the arms 25 and 26 and engages series of notches 35 formed in the inturned flanges of the face plates as shown in Fig. 6 and Fig. 7, thereby retaining said arms in their correct positions while the ticket is being printed and the bet indicated on the numeral drums 36 Fig. 4 in a manner to be explained later.

The printing wheels 29 and 30 already referred to, have a series of slots 37 corresponding to the number of competitors provided for, said slots being adapted to receive in a known manner printing type (not shown), bearing the numbers of the various competitors in a race or races, and one for "Win" and one for "Place" if a win and a place tote are provided for.

A locking plate 38 is secured to each of the printing wheels 29 and 30, each having notches 39 formed in their periphery, the number of notches corresponding to the number of slots 37 in the printing wheels 29 and 30, said notches 39 being engaged by a pawl 40 which ensures correct alignment of the respective parts during printing of the ticket. One pawl 40 is pivotally mounted at 304 below the locking plate 38 as shown in Fig. 8 so as to engage the notches 39 therein. A similar pawl 40 is mounted below the plate for locking the printing wheel 30 and the latter pawl is shown in Fig. 8a.

The respective pawls 40 are moved into and out of engagement with the notches 39 in the respective locking plates 38 on the printing wheels 29 and 30 by the action of a cam 148 acting upon a roller 42 mounted to actuate both pawls 40. The clutch member 41 is secured to the shaft 43 of the control handle 44.

A printing anvil 45 of known construction is pivoted upon one of the face plates and is engaged with the type, when inserted in the slots 37 of the printing wheels 29 and 30, by the action of a roller 46, shown in Fig. 9 carried in a cam 47 which is keyed on the shaft 43 of the control handle 44. The ticket strip 48 is fed in between the anvil 45 and the printing wheels 29 and 30 as shown in Fig. 9 and passes through the ejecting rollers 49 and 50 to the investor.

Selecting contacts 51, 52, 53, 54 and 55 are seen at the left of the control handle shaft 43 these being mounted on a movable contact member 56 formed as illustrated in Fig. 14 said member being carried by an assembly 146 mounted free upon the control shaft 43 and operated by the clutch member 41 fixed on the shaft 43. The clutch member 41 rotates the assembly 146 in an advance direction but is capable of returning free of the assembly 146 and leaving it in an engaged position under the retention of a locking pawl 147 which is arranged to engage the cam 148 as shown in Fig. 8a. In other words when the shaft 43 is rotated in the direction of the arrow shown in Fig. 8a the assembly 146 is driven by clutch member 41 and the roller 42 is engaged by the cam 148 to move the pawls 40 into the notches 39 in the locking plates carried by the printing wheels 29 and 30. The assembly 146 is retained in such rotated position by the pawl 147 which is urged into engagement with the detent 201 by a spring 202. As the shaft 43 is returned to a normal position the printed ticket is ejected by some known type of ejecting mechanism, not shown, and a ratchet tooth 203 on the clutch member 41 is engaged by a pawl 204 which prevents further operation of the control shaft 43 until the assembly 146 returns to a normal position and releases the pawl 204. The assembly 146 is retained in the rotated position for the purpose of maintaining various electrical circuits as hereinlater described but the cam 148 is released when the coil 104 is energized to withdraw the pawl 147. Thereafter the assembly 146 and the cam 148 are returned to inoperative positions by means of a spring 205. Such clockwise rota-

tion of the assembly 146 and the cam 148 is arrested by a pin 206 and during the retraction of the assembly a portion 207 of the cam 148 swings the pawl 204 to free the clutch member 41 for further operation.

Corresponding contacts 57, 58, 59, 60 and 61 mounted on the frame 68 are adapted for engagement by the contacts 51, 52, 53, 54 and 55, and are adapted to receive terminals for external connection. The contacts 57, 58, 59, 60 and 61 are mounted in a "Vulcanite" or the like insulated disc 69, as shown in Fig. 13. Fiber bushings are used throughout to insulate the various contacts from the frame 68 of the machine and the movable contact member 56.

The five moving contacts 51, 52, 53, 54 and 55 rotated by the assembly 146 and the corresponding fixed contacts 57, 58, 59, 60 and 61 are provided for the purpose of completing the circuits from the selector switch arms 25 and 26 to the controlling mechanism, Fig. 3, and indicating devices Fig. 4, and for the means under their control.

One of the selector switch arms 25 may engage additional contacts 70 and 71. The contact 70 being utilized when a ticket is sold representing a bet that a particular competitor will "Win" the event, and the other contact 71 will be utilized when a ticket is sold representing a bet that a particular competitor will finish second or "Place" in the event. The other selector switch arm is set on the number of the competitor which is being backed for a Win or Place. To facilitate this description the two additional contacts 70 and 71 will be hereinafter referred to as the "Win" and "Place" contacts 70 and 71 respectively.

Assuming that eighteen competitors are to be provided for in each of two races for which doubles tickets are to be sold, the face of the totalizer, Fig. 5, is divided horizontally into 18 spaces each space representing a horse in one race and vertically into 18 spaces eleven of which are shown in Fig. 5. The intersection of the horizontal and vertical places form minor spaces. Each minor space, therefore, represents a horse in one race and a horse in a second race and thereby forms pairs. For example, the upper space 181 in Fig. 5 represents horse No. 1 in one race and horse No. 18 in the other race. In each minor space there is a solenoid operated indicator, as shown in Fig. 4 which may be in the form of numeral drums 36 of well known construction. When the totalizer is also to be used for a "Win" and "Place" totalizer "Doubles" 55 separate spaces 72, and corresponding solenoid operated indicators, must be provided in the face of the totalizer, for each competitor in one particular race, under the designation "Win," and a similar set of spaces 73 and indicators under the designation "Place" as shown at the upper left corner of Fig. 5. The spaces so designated may be arranged in horizontal rows parallel with those previously referred to and immediately below and in association with the upper row of numerals representing the several horses in one race.

Current controlling apparatus

In order that two or more impulses from different ticket selling stations may not be transmitted to the indicating apparatus simultaneously apparatus which may be referred to as current controlling means, has been provided which includes the switches shown in Fig. 3. The current controlling apparatus necessary for the four

stations, as in the present example, consists of three sets of separately operated controls or switches 139, 140 and 141. In each set 139, 140 and 141 there are eight terminals, four being disposed on the right and four being disposed on the left as seen in Fig. 3, the controls in each set being operated in two directions, left or right, by respective electro-magnets 120, 119, 107, 121, 106, and 122 and the shafts 143.

From this it will be seen that the invention ensures that only one set of contacts can be connected at one time, and in the event of both magnets of each set being energized simultaneously, the terminals can only move in the one direction according to which magnet gets the advantage when energized.

Distributing device

To actuate the aforesaid solenoid operated indicators shown in Fig. 4, and on the face of the totalizer seen in Fig. 5, there is a distributing device embodying a plurality of oscillating drums 74 as illustrated in Fig. 2 one for each of the horizontal rows of indicators of the "Doubles" totalizer and one each for the "Win" totalizer and "Place" totalizer seen in Fig. 5.

Each oscillating drum 74, shown in greater detail in Fig. 10, is mounted eccentrically at 75 in a framework 76 and has a row of contacts 77 electrically connected to the respective contacts 23, which are under the control of wiper contact 28 of switch arm 26.

Arranged to engage the contacts 77 on the drums 74 is a plurality of resilient arms 78 shown in Figs. 10 and 15 which are secured on an insulated backing piece 79, said resilient arms 78 each being electrically connected to the respective solenoids 80, of the horizontal rows of indicators for which the oscillating drum 74 is provided.

Each of the drums 74 is maintained in its normal position by means of a spring 81, as shown in Fig. 2, and is oscillated by means of a respective solenoid 82 which derives current from the respective contacts 23, which are engaged by the wiper 27 of the selector switch arm 25, of the particular ticket issuing machine in operation.

Numeral drums

The numerical indicators or drums 36, which are shown in Figs. 4 and 11, are disposed in groups of three to represent units, tens and hundreds, each units drum being rotated by a solenoid 80 which is electrically connected to the distributing device of Fig. 2.

An aperture or window 181 is provided as usual, in the face 182 of the totalizer, for each indicator or group of drums 36, each of said groups of drums being mounted upon a shaft 83 carried in bearings such as 84 and 85 said bearings being secured upon a shelf 86 bolted to the rear face of the totalizer.

The solenoid 80, which is securely attached to the rear surface of the totalizer actuates a plunger 87 which is slidable in a bifurcated upright 88 also supported on the shelf 86. The bifurcated upright 88 has secured thereto an insulating block 89 of "Vulcanite" or the like to which are pivoted three metal contact arms 90, 91, 92 said arms 91 and 92 having contact screws 93 and 94 respectively.

On the under side of the plunger 87 which is preferably of square or rectangular formation, a short lug 95 is formed integral therewith. An abutment screw 96, parallel with the plunger 87

and threaded through the lug 95 is adapted to strike a lever 97 pivoted at 98 to a fitting 99 on the shelf 86. A pawl 100 is pivotally mounted on the lever 97 and engages a ratchet wheel 101 secured to the shaft 83 upon which the drums 36 are mounted. A spring 100a is provided for returning the lever 97 to an inoperative position when the coil 80 is deenergized.

The units numeral drum 36 in Fig. 4 and shown at the left in Fig. 11 is rotated upon energization of the coil 80 which moves the plunger 87 and the pawl 100 to thereby rotate the shaft 83 and the units drum 36 secured thereto. The units drum 36 is rotated by electrical impulses impressed across the coil 80 and the numeral nine will eventually appear in the aperture or window 181 before the tens numeral drum 36a is actuated it being understood that the drums of denominations above units are rotatable on the shaft 83. The mechanism for transferring movement to the tens drum 36a is known in the cycloometer art and such means includes a pin 37a, a transfer-wheel 33a and pins 39a. The arrangement is such that the units drum 36 describes an arc of 360 degrees for every ten impulses of the plunger 87 and then the tens drum 36a is rotated by means of the pin 37a and the transfer-wheel 33a and the pins 39a one-tenth of one complete revolution. A similar arrangement is provided for transferring one complete revolution of the tens drum 36a to the hundreds drum 36b. The tens and hundreds drum are mounted for free rotation on the shaft 83 and means such as the depending resilient arms 40a are provided 35 for preventing inadvertent rotation of these drums.

Referring again to Fig. 4, the plunger 87 has a roller 102 mounted thereon, which engages the central contact arm 91 during the inward movement of the plunger 87 when the solenoid 80 is energized. On this movement taking place the arm 91 moves about its pivot 103 and the contact screw 93 engages the arm 99 thereby closing a circuit which supplies the necessary current to the coil 104 so as to release the pawl 147 during actuation of the plunger 87 whereby the numeral indicator formed of the drums 36 is operated before the assembly 146 is permitted to return to an inoperative position. The release of the pawl 147 from the cam 148 frees the machine for operation with respect to the next investment. The plunger or armature 87 is withdrawn or returned to an inoperative position by means of a spring 288 as shown in Fig. 4.

The contact arm 92 supplies current to a signal device such as a lamp 210 which remains energized in the event the plunger 87 does not return to the inoperative position by the spring 288 when the coil 80 is no longer energized. Thus the fault may be traced and corrected. The lamp 210 is energized when the contact screw 94 engages with the lower part of the arm 91 and the plunger 87 is in its inward position, one terminal of the lamp being connected with negative potential and the other with positive potential through the arm 91. The contact is broken when the plunger 87 returns to rest.

Supposing a person backs say No. 1 competitor to win the race. He approaches a ticket window. The ticket vendor will move the switch arm 25 to engage the "Win" contact 70, and he will move the switch arm 26 to engage No. 1 contact thereof as shown in Fig. 15.

When the switch arm 25 is moved to engage the "Win" contact 70 the printing wheel 29 is

rotated so as to position a type carrying the letters "Win" over the strip 48. Rotation of the switch arm 26 so as to engage the No. 1 contact will also cause the printing wheel 30 to position a type therein bearing "No. 1" over the ticket strip 48. Thereafter the control handle 44 is actuated to rotate the shaft 43 and the clutch member 41. During such rotation of the shaft 43 the cam 148 is rotated to raise the pawls 40 into notches 39 in locking plates 38. The spring 202 then moves the pawl 147 to engage the detent 201 of the cam 148. Thus the assembly 146 is maintained in a rotated position.

The insulating member 56 is rotated during turning of the assembly 146 so that the contact 55 engages the contact 59 and the contact 51 engages the contact 57. The contacts 60, 61 and 58 are then bridged by means of a conductor 200 which connects the contacts 52, 53 and 54. Thus positive current which is supplied to the contact 61 is also supplied to the contact 58 through the conductor 200 and to one terminal of the coil 107 through the conductor 401 and the other terminal of the coil 107 is connected to the negative side of the line by a wire 402. Thus the lower selector switch group 141 is swung downwardly on the left whereby the switch blade 110 engages the terminal 112 and the switch blade 111 engages the terminal 113. The switch blade 116 makes contact with the terminal 115 and the switch blade 132 is electrically connected to the terminal 131.

Positive current is also supplied to the contact 60 through the conductor 200 and this positive potential is supplied through the conductor 221 to one terminal of the coil 106 and this coil is energized since the other terminal thereof is connected to the negative side of the line by a wire 410. Thus the group of switches 140 is swung downwardly to the right and the switch blades thereof engage the terminals at the right side thereof in Fig. 15.

Positive current is supplied to the central portion of the switch blade 108 which is then engaging the terminal 222 and this positive current passes along the conductor 223 to the switch blade 110 and therethrough to the terminal 112 through the conductor 224 to the contact 59. The contact 59 is then in engagement with the contact 55 so that positive current is then conducted through the wire 225 to the wiper contact 27 and the contact 70. This positive potential is applied through the conductor 226 to a solenoid coil 82 in the distributor assembly corresponding to "Win." Positive potential is also supplied to the contact wiper arm 28 through the switch blade 109 and the terminal 227 and the conductor 228 through the switch blade 111. This circuit then extends through the contact 113 and the conductor 229 to the contact 57 and the contact 51 and the conductor 230 to the contact 23 opposite the No. 1 competitor. A conductor 231 extends from this contact 23 to a terminal 114 in the distributing mechanism.

When the coil 82 is energized the associated drum 74 is rotated so that the contacts 77 engage the blades 78. A conductor 233 extending from one of the contacts 78 to the coil 80 of one of the totalizers supplies positive current to the coil 80 and the other terminal of this coil is connected to the negative side of the source. The coil 80 actuates the plunger or armature 87 so as to rotate the numeral drum 36 one unit corresponding to the selection made by the switch arms 25 and 26 and the actuated distributor assembly.

When the arm 91 and the screw 93 thereof

engages the contact arm 90 positive current is supplied to one side of the coil 104 through a wire 234 and the other terminal of the coil 104 is connected to the terminal 115 of the lower selector switch 141 by means of a conductor 236 and the circuit is thus established to the switch blade 116 and the conductor 235 to the terminal 117 and the switch blade 118 and to the negative side of the source so that the coil 104 is energized and the pawl 147 is retracted whereby the spring 205 will return the assembly 146 to an inoperative position. It is to be noted, however, that the coil 104 cannot be energized until the proper drum 36 has been actuated.

After the coil 104 has been energized and when the assembly 146 is returned to an inoperative position by means of the spring 205 the contact member 56 is rotated to interrupt the circuit supplying a positive potential to the contacts 58 and 60 from the terminal 61. Under such circumstances the coils 106 and 107 would normally be deenergized and release the switch groups 140 and 141 for turning movement if the coils 119 and 122 are then energized by some other ticket issuing machine. Such release of the group switches 140 and 141 is prevented by means of a relay 127. The coil of this relay 127 is energized when the distributor drum 74 is actuated by the coil 82. A positive potential is then supplied through the closed contacts 123 and 126 to establish a circuit through the conductor 420 through the coil of the relay 127 and the other terminal thereof is connected by conductor 421 to the terminal 131. The circuit of the coil of the relay 127 is then completed through the switch blade 132 and a conductor 422 through the terminal 133 and through the switch blade 134 to the negative side of the supply. Thus the relay 127 is energized when the distributor drum 74 is actuated. The switch blade 423 of the relay 127 is connected to the positive side of the source and when this blade engages the contacts 130 and 135 positive potential is supplied through the conductor 424 to one terminal of the coil 106 and positive potential is also supplied through the conductor 425 to one terminal of the coil 107. Since the other terminals of the coils 106 and 107 are connected to the negative side of the supply these coils remain energized even though the positive potential is no longer supplied through the conductors 401 and 221. The switch group 140 thus remains in the position shown in Fig. 15 and the group switch 141 also remains with the blades thereof in engagement with the contacts shown at the left in Fig. 15. The group switches 140 and 141 cannot therefore be utilized for operation by other ticket issuing machines until the drum of the distributor 74 returns to an inoperative position.

The coil of the relay 127 is also energized from the positive side of the source connected to the arm 91 when the armature 87 swings this arm 91 in engagement with the screw 94 so as to supply positive potential to the coil of the relay 127 through the wire 426 and the conductor 420. This circuit is maintained if the armature 87 does not return to an inoperative position and the double throw switches 140 and 141 are thus not released until the drum 74 of the distributor assembly returns to an inoperative position and after the arm 91 is disengaged from the contact screw 94. Such means prevents the operation of the ticket issuing machines in the event that the indicating drum mechanism which includes the armature 87 becoming jammed or in the event

the distributor drum 74 fails to return to an inoperative position.

The invention includes signal means for indicating the failure of the armature 87 to return to a normal inoperative position and such means may include the lamp 210 which will continue to remain illuminated in the event that the armature 87 becomes jammed.

When the contact member 56 and the assembly 146 return to an inoperative position the circuit through the conductor 226 is interrupted since the contact 55 no longer engages the contact 59. Thus the coil 82 is de-energized and the drum of the distributor assembly is thus normally returned to an inoperative position by means of the spring 81. The circuit to the coil 80 is thereby interrupted and the armature 87 will normally return to an inoperative position by means of the spring 208. The coil of the relay 127 will thereby be de-energized and the supply circuits to the coils 106 and 107 will thus be interrupted by downward movement of the switch blade 423 and the blades of the group switches 140 and 141 will thereby be free for movement to engage the contact at either of the sides thereof.

Similarly, should a person back No. 1 competitor for a place, the vendor will move the switch arm 25 to the "Place" contact 71, and the switch arm 26 to its No. 1 contact. The operation of the mechanism when a "Place" bet is made on a No. 1 competitor or horse is similar to the operation hereinabove described except that a different solenoid 82 of the distributor mechanism is energized through the wire 440 and current is supplied to a solenoid 80 corresponding to a "Place" bet on a No. 1 competitor. In this case the ticket issuing mechanism is likewise not free for further operation until the coil 104 is energized.

If a "Doubles" investment is called for which is assumed to include a competitor No. 10 in one race and a competitor No. 5 in another race each machine may be used for this purpose. In operation of the totalizing system and a ticket issuing machine for such a "Doubles" selection the operator moves the switch arm 25 to the No. 10 contact 23 as shown in Fig. 16 and the switch arm 26 is moved to the No. 5 contact 23. During the swinging movement of the switch arms 25 and 26 the printing wheels 29 and 30 are moved so as to position the type bearing No. 10 and No. 5 over the ticket strip 48. When the handle 44 is operated in a manner hereinabove described the pawls 40 are actuated to maintain the printing wheels in the selected positions and the ticket is printed. The operation of the handle 44 also causes the contact member 56 to be rotated whereby the contact 51 engages the contact 57 and the contact 55 engages the contact 59 and the conductor 200 bridges the contact 58, 60 and 61. Positive current is then supplied from the contact 61 to the contact 60 through the conductor 221 to one terminal of the coil 106 and since the other terminal thereof is connected to the negative side of the supply the switch group 140 is moved downwardly to the right in Fig. 16. The contact 58 is also supplied with positive potential from the contact 61 through the conductor 200 and this positive current passes through the conductor 401 to one terminal of the coil 107 and the other terminal thereof is connected to the negative side of the supply by the conductor 402. Thus the group switch 141 is moved downwardly and to the left in Fig. 16.

The central portion of the switch blades 108

and 109 are connected to the positive side of the source and a positive potential is thus supplied through the terminal 222 and the conductor 223 to the switch blade 110 and the terminal 112 and through the conductor 224 to the contact 59 which is then in engagement with the contact 55. This circuit extends from the contact 55 through the conductor 225 to the wiper blade 27 which is then in contact with No. 10 contact 23. This positive current is then supplied through a conductor 450 to the solenoid 82 corresponding to No. 10 of the distributor mechanism so that the related drum 74 is operated.

Positive potential is supplied to the wiper arm 28 through the switch blade 109, the terminal 227, the conductor 228, the switch blade 111, the contact 113, the conductor 229, the contact 57, the contact 51 and the conductor 230. Since the wiper blade 28 is in engagement with the No. 5 contact 23 positive potential is supplied to the conductor 451 which is connected to one of the terminals 114 of the distributor assembly and through a conductor 452 to the No. 5 contact 71 of the No. 10 drum 74. The associated contact 78 is connected by means of a wire 453 to a solenoid 80 in the totalizer at the intersection in the No. 10 and No. 5 rows. This solenoid 80 is therefore energized to operate the numerical indicator 36. Thus the "Doubles" bet has been properly indicated on the totalizer.

The ticket issuing machine providing the impulse to the coil 80 at the intersection of the No. 10 and No. 5 rows on the totalizer will not be freed for further operation until the armature 87 thereof has been actuated to close the contacts 90 and 93. When positive potential is supplied to the arm 90 a circuit is completed through the conductor 254 and the wire 455 to one terminal of the coil 104 of the machine which is in operation and the other terminal of this coil is connected by a conductor 236 to the terminal 115 and the circuit then extends through the switch blade 116 and the conductor 235 to the terminal 117 and the switch blade 118 to the negative side of the source so that the coil 104 is energized and contact member 56 is returned to an operative position in a manner as hereinabove described. The coils 106 and 107 however remain energized even though positive potential is no longer supplied to the conductors 221 and 401 since the relay 127 is energized as long as the associated drum 74 and the associated armature 87 remain in their operative positions. For example positive current is supplied to the contact 126 and through the conductor 420 to the coil of the relay 127 and the other terminal thereof is connected to the terminal 131 by means of the conductor 421. The circuit for the coil of the relay 127 extends through the switch blade 132 and the conductor 422 to the terminal 133 and through the switch blade 134 to the negative side of the source. The relay 127 is also energized when the contacts 94 and 91 of the numerical indicator which has been actuated close. This circuit extends through the conductor 451. When the relay 127 is actuated positive potential is then supplied to the terminals of the coil 107 and 106 through the conductors 424 and 425. Thus the group switches 140 and 141 remain in the first operated positions until the No. 10 distributor mechanism and the numerical indicating drums at the intersection of the No. 10 and No. 5 rows on the totalizer (Fig. 5) have returned to their inoperative position.

The invention includes means for preventing

simultaneous operation of several of the ticket issuing machines to thereby prevent false indications on the totalizer of the number of tickets issued. In other words the invention includes means for preventing two machines from being actuated simultaneously so that in effect only one impulse would thereby be produced in one of the coils 80. Such means includes as an essential feature thereof the double throw group switches shown in Fig. 3 and partly illustrated in Fig. 16.

If the ticket issuing machine A diagrammatically represented at the left in Fig. 16 and the ticket issuing machine diagrammatically represented at B in Fig. 16 and the handles 44 thereof are actuated at substantially the same instant one of these machines will be supplied with positive current for the switch blades 27 and 28 while the other machine will remain in condition for being supplied with positive current to the switch blades 27 and 28 after the first machine has completed its operation of the proper numeral indicating mechanism on the totalizer.

For such purposes the air gaps between the magnets 107 and 122 and the switch blade 132 are for example slightly different so that in the event both coils 107 and 122 being simultaneously energized the group switches will be first actuated by the electromagnet having the smaller air gap. In a like manner the air gap between the magnet 106 and the switch blade 134 is smaller than the air gap for the magnet 119.

If it is assumed that the group switch 140 has been moved downwardly and to the right by energization of the coil 106 by the ticket issuing machine A in a manner as hereinabove described and if the control handle 44 of the B machine is operated simultaneously with the control handle 44 of the A machine the coils 107 and 122 will be simultaneously energized since positive potential is then supplied from the terminal 61 in the B machine to the contact 58 in the B machine and through the conductor 460 to one terminal of the coil 122 and the other terminal thereof is connected to the negative side of the line by the conductor 461. The group switch 141 however will be moved downwardly and to the left in Fig. 16 since the air gap of this electromagnet is slightly smaller than the air gap of the electromagnet 122. Thus the "Doubles" representing a No. 10 and No. 5 competitor as set up in the A machine will be indicated by energization of the coil 80 in the totalizer at the intersection of the No. 10 and No. 5 rows as hereinabove described. When the coil 107 is no longer energized and when the drum 74 and the armature 87 of the No. 10 and No. 5 combination have returned to their inoperative positions the B machine becomes operative to send its impulses to the proper coil 80 of the totalizer.

After the group switches 141 are released by the coil 107 the positive potential supplied through the contact 58 in the B machine and through the conductor 460 will cause the coil 122 to move the group switches 141 downwardly and to the right in Fig. 16. The positive potential supplied to the contact 60 in the B machine will also maintain the coil 106 energized and hold the group switches 140 downwardly and to the right in Fig. 16. Positive current is also supplied to the wiper blade 27 in the B machine through the switch blade 108 and the terminal 222, the conductor 223, the switch blade 110, the terminal 470 and the conductor 471 to the contact 59 in the B machine which is then in engagement with

the contact 55 in the B machine and this contact is connected to a wiper arm 27 by means of a conductor 472. This positive potential may then extend from the No. 9 contact 23 in the B machine through the conductor 473 to a solenoid 82 in the distributor mechanism corresponding to a No. 9 competitor.

Positive current is also supplied to the wiper arm 28 through the switch blade 109, the terminal 221, the conductor 228, the switch blade 111, a terminal 474, a conductor 476 to the contact 57 in the B machine. This contact 57 is then in engagement with the contact 51 of the B machine so that the positive potential is applied to the wiper arm 28 which may then for example engage a No. 4 contact 23 in the B machine and this positive potential is applied through a conductor 480 to one of the terminals 114 and a corresponding contact 77 on the distributor drum 74. This positive impulse of the B machine is then applied to a coil 80 at the intersection of the No. 9 and No. 4 rows of the totalizer through a wire 481.

When the No. 9 distributor drum 74 is actuated or when the armature 87 of the No. 9 and No. 4 totalizer is operated a relay 128 is energized to maintain the coils 106 and 122 energized even though the contact member 56 of the B machine returns to an inoperative position. It will be further noted that the coil 104 of the B machine is not energized to release this machine for movement to an inoperative position until the contacts 90 and 91 of the No. 9 and No. 4 indicating device are closed. When these contacts are closed positive potential is applied to the conductor 234, a wire 290, the coil 104 of the B machine, a conductor 291, the terminal 492, the conductor 235, the terminal 117, the switch blade 118 to the negative side of the supply.

While the invention has been described with reference to specific types of switches and with regard to various types of mechanical equipment it will be appreciated that changes may be made in the switch mechanisms without departing from the scope of the invention which pertains particularly to the circuits hereinabove described. Various changes may be made in the structural and mechanical features of the totalizer without departing from the spirit and scope of the invention as set forth in the appended claims.

I claim:

1. In an electric totalizer the combination with a plurality of machines each provided with class bet selecting means operable to send an electric impulse selectively over any one of a plurality of class wires connected in common to all machines, class bet receiving relays one for each class and each directly connected in circuit in the corresponding common class wire and responsive solely to an electric impulse sent over said wire, an actuating electromagnet for operating a counter for each competitor in each class, a circuit control means associated with the machines operable to initiate an impulse identified solely with the competitor upon which a bet is set up on the machine, means including the class bet receiving relay operable to cause the energization of the actuating magnet for the competitor counter in the appropriate class by a competitor impulse so initiated, and means controlled by said actuating electromagnet operative to render the circuit control means ineffective following operation of said counter and means

rendered operative upon initiation of operation of one of said machines to prevent the other machine from sending impulses over said class wires.

2. In a totalizer, registering means, actuating means for said registering means, a plurality of machines, two separately settable bet selecting means associated with each machine, means for operating the actuating means of said registering means including electric circuits extending from the bet selecting means of each machine to said registering means, double throw switches connectable with a current source, means operable upon operation of any machine for throwing said switches to a position to supply current to the bet selecting means of one machine only whereby said registering means is operated before another machine can become operative to supply current from the source to a registering means, releasable detent means retaining said switch operating means in a position holding said switches in said position, means for re-

leasing said detent means upon operation of said registering actuating means, and means retaining said switches in said position until the registering actuating means moves to an inoperative position.

ROY E. WELLS.
